Palmer S. Dahl Inventor

UNITED STATES PATENT OFFICE.

PALMER S. DAHL, OF EVERETT, WASHINGTON.

PIN.

1,405,500.

Specification of Letters Patent. Patented Feb. 7, 1922.

Application filed July 13, 1921. Serial No. 484,369.

To all whom it may concern:

Be it known that I, PALMER S. DAHL, citizen of the United States, residing at Everett, in the county of Snohomish and State of Washington, have invented certain new and useful Improvements in Pins, of which the following is a specification.

This invention relates to pins and more particularly to an improved construction for permitting the pin to be inserted in the cloth or other material in a manner that will prevent it from being accidentally or casually displaced.

Other objects will appear upon consideration of the following detail description and accompanying drawings, whereon:

The figure illustrates a side elevation of the pin showing the same mounted in a strip of cloth.

The pointed shank 1 has its free end provided with the pin point 2 and its upper end is rearwardly curved to form an offset 3 from which a portion of the pin is extended straight as indicated at 4, this portion being offset with respect to the shank of the pin, but in parallel relation thereto. From the upper end of this straight portion 4 a loop 5 is formed which serves as a guard and from which extends a connecting elbow 6 the terminal of which is equipped with the pin head 7. A slight space intervenes between the straight portion 4 and the parallel portion of the elbow 6.

The cloth or other material indicated at 8 receives the pin in a manner that will prevent the pin from working out of the

cloth after it has been placed in position. The irregular contour serving to prevent the pin from reciprocating or working out by an up and down movement. The elbow portion 6 should be constructed with respect to its length so as to permit the cloth to slip over the guard member 5 when the pin is being removed.

Minor changes may be made in the details of construction without departing from the spirit of the invention or the scope of the claim hereunto appended.

What is claimed is:

A pin comprising a pointed shank having its upper end curved to provide an offset, a straight portion extending upwardly from the offset in parallel relation to the said shank, a pin head, a right angular elbow portion having one end connected to the pin head, a loop guard member forming an integral part of and connecting the ends of the said elbow and straight portion, a portion of the elbow being parallel to and spaced from the said straight portion above the offset, the length of the portion connected to the said pin head being sufficient to permit the said loop guard member to readily follow through an opening through which the pin passes.

In testimony whereof, I have affixed my signature in the presence of two witnesses.

PALMER S. DAHL.
